UNITED STATES PATENT OFFICE

2,069,587

MEANS FOR STARTING AN INTERNAL COMBUSTION ENGINE

Heinrich Maurits Meier Mattern, Hilversum, Netherlands, assignor of part to Werkspoor N. V., Amsterdam, Netherlands

Application January 26, 1933, Serial No. 653,725
In the Netherlands February 1, 1932

13 Claims. (Cl. 60—16)

This invention relates to a device for starting an internal combustion engine by supplying compressed air into the engine cylinder, its chief object being a cheap and reliable device which 5 is simple, quick and foolproof in operation.

With this and other objects in view, I suggest to hydraulically actuate the starting valve by means of the fuel under pressure supplied by the fuel pump in such a manner that the 10 hydraulic system, which comprises an active piston and a passive piston adapted for cooperation therewith, includes a change-over member adapted, when assuming its starting position, to have the plunger of the fuel pump function as 15 the active piston of said system.

Said change-over member may be provided in the delivery pipe of the fuel pump. However, since ordinarily very high pressures occur in 20 said pipe so that the provision of a control member therein is likely to result in leakage, I prefer to mount said member in a special pipe connecting the pump chamber with the starting valve casing, or, better still, in the suction pipe 25 of the pump. Alternately, the change-over member may be the fuel pump plunger itself, which, with a view thereto, may be adapted for rotation about its own axis and provided with the required ports.

In order that my invention may be readily 30 understood by those skilled in the art, I shall now proceed to describe the same in detail with reference to the drawings, in which:

Fig. 1 is a diagram of a fuel pump, part of a combustion engine cylinder with fuel valve and 35 starting valve, connections between said valves and the pump, and a change-over member in the delivery pipe of the pump, said member being shown in starting position,

Fig. 1A is a diagram of said change-over member in the position which it assumes during 40 normal operation of the engine,

Fig. 2 is a diagram of a fuel pump with its 45 connections to the fuel valve and the starting valve of the engine cylinder, and a change-over member mounted in a special pipe between the pump chamber and the starting valve casing,

Fig. 3 is a diagram of another embodiment of 50 the invention, in which the change-over member is mounted in the delivery pipe of the pump,

Fig. 3A is a section of said change-over member in the position which it assumes during 55 normal operation of the engine,

Fig. 3B is a diagrammatic side elevational view 60 of the cam for actuating the pump plunger shown in Fig. 3,

Fig. 4 is a diagram of still another embodiment of the invention, in which the change-over member is mounted in the delivery pipe of the pump,

Fig. 5 is a diagram of a fuel pump, its connections with the fuel valve and with the starting 5 valve, and a change-over valve mounted in the suction pipe of the pump,

Fig. 5A is a side view of the pump plunger shown in Fig. 5 on an enlarged scale,

Fig. 6 is a diagram of part of an engine 10 cylinder with fuel valve and starting valve, in which the change-over member is mounted in the suction pipe of the pump and forms the passive hydraulic piston through which the starting valve is actuated,

Fig. 7 is a diagram of a fuel pump, the plunger of which is adapted for rotation about its own axis and provided with ports through which the pump chamber can be put into communication with the starting valve casing,

Figs. 7A and 7B are a diagrammatic end view 20 and a side elevational view, respectively, of the cams for actuating the pump plunger shown in Fig. 7,

Fig. 7C is a side view of the pump plunger 25 shown in Fig. 7 on an enlarged scale,

Fig. 8 is a diagram of another modification in which parts of the engine cylinder are also shown,

Fig. 8A is a diagrammatic side view of the 30 pump plunger shown in Fig. 8,

Fig. 8B is a cross section of the plunger on the line VIII^B—VIII^B in Fig. 8A,

Fig. 9 is a diagram showing a fuel pump, arranged substantially as the one illustrated in 35 Fig. 8, in combination with a special starting pump adapted to be driven by compressed air,

Fig. 9A is a diagrammatic detail view of the 40 plunger of the fuel pump shown in Fig. 9, on an enlarged scale, and

Fig. 9B is a longitudinal section of the pump 45 plunger in its starting position,

Fig. 10 is a diagrammatic view of still another embodiment, in which the plunger of the fuel pump forms the change-over member.

Fig. 10A is a detail view of the distributing 50 valve used in the arrangement shown in Fig. 10 in the position during normal operation.

In Fig. 1, the numeral 1 designates the fuel valve of the engine cylinder, 2 the starting valve 55 of said cylinder, and 3 the fuel pump. The fuel valve and the starting valve are connected with the fuel pump by pipes 4 and 5, respectively, through a common cock 6 adapted to be turned by a handle 7. According to the position of said 55

cock 6, the fuel supplied by the pump 3 is injected through valve 1 into the motor cylinder, or used for hydraulically actuating the starting valve 2.

5 During operation of the engine, a shaft 8 provided with a cam 9 serves for periodically lifting a spring loaded pusher 10 movable in a cylindrical guide 11 and associated with the pump plunger 12. The pump is further provided with 10 a suction valve 13 connected through a pipe 14 with the fuel tank 15.

The amount of fuel supplied at each working stroke of the pump 3 is controlled by means of a rod 16 adapted to engage a cam lever 17 having 15 a pin and slot connection with the pump plunger 12 and eccentrically pivoted as at 18 to a shaft 19, adapted to be adjusted manually (Fig. 4) by means of a handle 19b or automatically by the 20 governor, 19a (Fig. 1) during the operation of the engine.

Rod 16 is adapted, when lifted by cam lever 17 during the delivery stroke of plunger 12, to unseat the suction valve 13 and thereby to cut off the supply of fuel through the delivery 25 valve 20.

Normally, the fuel delivered by valve 20 flows 30 through a pipe 21, cock 6 and pipe 4 to the fuel valve 1, the needle 22 of which is adapted to be lifted under the action of the hydraulic pressure 35 of the liquid fuel acting on the lower side of the piston-like body of the valve 22 in order to allow the fuel to be injected into the cylinder of the engine.

In order now that also the starting valve 23 35 may be actuated by the fuel supplied by pump 3, its casing comprises a small cylinder 25 in which a plunger 24 is adapted to reciprocate and which is connected near its top with pipe 5. If change-over cock 6 assumes the position shown in Fig. 1A, 40 said pipe 5 communicates with a pipe 26 branched off from suction pipe 14. Moreover, cock 6 is connected to a pipe 27 which directly opens into the pump cylinder.

In normal operation of the engine, i. e. with 45 cock 6 in the position shown in Fig. 1A, pipe 27 is shut off, but with the cock 6 in starting position (Fig. 1), pipe 27 communicates with pipe 5, pipe 21 is shut off, and pipe 4 communicates with pipe 26, i. e. with the fuel tank, so that no fuel 50 can be injected into the cylinder of the engine through fuel valve 1.

During starting, the means for positively lifting the suction valve 13 may assume a position responsive to the maximum supply of fuel for 55 normal operation, or it may be set in a special position, for instance so that suction valve 13 is not lifted at all during the cycle of plunger 12. Now, with change-over cock 6 in the position shown in Fig. 1, the fuel delivered by the pump 60 will flow through said cock and pipe 5 to hydraulic cylinder 25, whereby plunger 24 is depressed against the action of a light spring 28, until it engages rod 29 of starting valve 23, whereupon said valve opens against the action of a 65 relatively strong spring 30, it being understood that the normal clearance between plunger 24 and valve rod 29 is adapted to be varied in accordance with requirements by adjusting the disk-shaped nut 29a on rod 29.

70 As soon as suction valve 13 is unseated during the delivery stroke of the pump, the hydraulic pressure on plunger 24 falls to zero, and valve 23 is again closed by its spring.

It will be understood that, if suction valve 13 75 is not opened at all during the cycle of plunger

12, the plunger 24 and the starting valve 23 will simply follow the movements of the pump plunger 12, i. e. valve 23 will be pressed upon its seat as soon as the return stroke of plunger 12 begins.

Starting of the engine is carried out as follows:

The flywheel of the engine is turned until the piston of the engine, or one of the pistons, approximately assumes the correct starting position. Change-over handle 7 is set to the position shown 10 in Fig. 1 and compressed air is supplied, through pipe 23a, to valve 23 by means of a starting valve not shown. Thereafter, the plunger 12 of the fuel pump, or with a multi-cylinder engine the plunger of the fuel pump corresponding to the 15 cylinder, whose piston assumes the correct starting position, is forced inward by hand, or by a suitable tool 12b, so that the fuel in pipe 5 depresses the plunger 24, which in turn opens the starting valve, whereby compressed air supplied 20 through pipe 23a is allowed to act upon the piston of the engine, the motor is started, and the starting valve or valves is or are further actuated automatically by the fuel pump or pumps.

When the engine has attained the required 25 speed, handle 7 is again set in the position shown in Fig. 1A, whereby fuel will be injected into the engine cylinders through the fuel valve or valves 1, while the starting valves remain seated. Thereafter the starting air valve referred to above 30 is closed.

In the following description and in the appended claims the plunger 12 will be called the "active" piston, and plunger 24 the "passive" piston of the 35 hydraulic system which serves to actuate the starting valve.

Fig. 2 illustrates part of a somewhat simplified arrangement, which is suitable, for instance, when direct fuel injection is used and the fuel injection pressure is high, it being understood 40 that actuation of the starting valve requires only a relatively low hydraulic pressure. In this case, the delivery valve of the fuel pump 3 is connected directly, and not by way of any valve member, with the fuel valve casing of the engine cylinder 45 through the delivery pipe 4. Pipe 32, which is the equivalent of pipe 21 in Fig. 1, is in direct communication with the pump chamber and through said pipe the fuel supplied by the pump is adapted to flow, through a cock 31 and pipe 5, to the cylinder for actuating the starting valve 23. Into the casing of cock 31 also opens a pipe 33, which is branched off from the suction pipe 14 of the fuel 50 pump.

In Fig. 2, the change-over cock 31 assumes its 55 starting position, in which pipes 32 and 5 are in communication with each other and pipe 33 is shut off. If, now, the plunger of the fuel pump performs its delivery stroke, the starting valve 23 will be forced off its seat, but the fuel valve 22 will 60 remain seated, since the last said valve requires a much higher hydraulic pressure for its actuation than does the starting valve.

If cock 31 assumes its normal position as indicated by a dotted line, pipe 32 is shut off and pipe 65 5 is in communication with pipe 33, so that no hydraulic pressure can act upon the "passive" piston. Consequently, the starting valve remains seated and the plunger of the fuel pump 3 acts exclusively upon the fuel valve of the engine.

The device shown in Fig. 3 comprises a fuel pump 35 of a somewhat different construction, and further a change-over valve for controlling the flow of the fuel supplied by the pump. In this arrangement, the stroke volume of the pump 75

is adapted to be controlled by adjustment of the length of stroke through axial adjustment of cam 36 (see Fig. 3B).

A piston valve 37 mounted in a cylindrical casting 38 is adapted to be lifted by a change-over handle 39. Opening into said cylinder are, on the one side, a pipe 40 connected through a delivery valve with the pump chamber, a pipe 41 directly connected with said chamber, and the suction pipe 42, on the other side the pipes 4 and 5 to the fuel valve and to the starting valve of the engine, respectively. The valve piston 37 has a circumferential groove 43 and also a central longitudinal passage 44 opening into the top and bottom faces thereof, a coiled spring 45 tending to keep said valve piston in engagement with handle 39. Said handle may be held in its position for normal operation by means of a clamping member (not shown) or by the friction about its pivot. In the position shown, which is the starting position, pipes 5 and 41 communicate through the circumferential groove 43, whereas pipe 40 is shut off and pipe 4 is connected, through passage 44, with suction pipes 14, 42. Consequently, the fuel valve is relieved from pressure and the fuel supplied by the pump flows exclusively to the starting valve of the engine.

Fig. 3A shows the position of the piston valve 37 when the engine is in normal operation. It will be seen that pipe 40 then communicates, through groove 43, with pipe 4, whereas pipe 41 is shut off and pipes 5 and 14, 42 are in communication with each other, so that the starting valve of the engine remains seated and the fuel supplied by the pump is exclusively forced to the fuel valve.

Fig. 4 shows a device comprising a fuel pump 46 of a somewhat different construction. As shown, the fuel pump is provided with a suction valve 47 and a delivery valve 48. In addition, it is equipped with a so-called spilling valve 49 for controlling the stroke volume of the pump, said spilling valve being adapted to be unseated at any desired moment during the cycle of the pump plunger under the influence of lever 17. As described with reference to Fig. 1 one end of said lever is connected with the pump plunger and the other end is eccentrically pivoted as at 18 to a shaft 19, adapted to be adjusted by means of handle 19b. The suction pipe 14 opens into the valve casing at a point below valves 47 and 49.

The pump has only one delivery pipe, designated by 50, which is connected with the pump chamber through the delivery valve 48. Said pipe 50 opens into the casing 51 of a change-over valve 52, but is in permanent communication with pipe 4 to the fuel valve of the engine cylinder. The space below valve body 52 is connected with the starting valve of the engine cylinder through pipe 5. Valve 52 is adapted to be manually unseated by means of a change-over handle 53, so that the fuel pump is adapted either to actuate the starting valve, or to inject fuel through the fuel valve into the engine cylinder, dependent upon whether valve 52 is unseated by handle 53, or seated under the action of a spring by which it is loaded.

Also in this embodiment, the operation of the device is based upon the fact that the pressure required for opening the fuel valve of the engine cylinder is much higher than that required for actuating the starting valve.

If one single delivery pipe is provided, which communicates with the pump chamber through the delivery valve of the pump, this valve should

be unseated during the operation of the starting valve of the engine cylinder, otherwise the starting valve could not again seat itself. With a view thereto, the change-over handle 53 is operatively connected, through a suitable lever system, 53a 5 53b, 53c, with a lever 54 provided with a cam 55 arranged to hold the delivery valve 48 unseated, through the medium of a rod 56, as long as the handle 53 assumes its starting position.

Figs. 5 and 6 illustrate embodiments of an arrangement wherein the pressure pipe of the starting valve of the engine cylinder is connected with the suction pipe of the fuel pump. It will be appreciated by those skilled in the art that such an arrangement has distinct advantages 10 over the constructions described with reference to Figs. 1, 3, and 4, in that the delivery pipe from the fuel pump to the fuel valve of the engine, which ordinarily is subjected to very high pressures, need now not be provided with joints, 15 which are always liable to leakage.

According to Fig. 5, the device comprises a fuel pump 57, in which the stroke volume is adapted to be controlled by rotation of the pump plunger about its axis. As shown, pump 57 is 20 directly connected with the fuel valve of the engine by means of the delivery pipe 4. The pipe 5, which runs to the starting valve casing of the engine, is branched off from the suction pipe 58 25 of the fuel pump.

The suction pipe 58 here is not in direct communication with the pipe 14 to the fuel tank, but is connected thereto through a valve 59 in a casing 60. By means of a change-over handle 61, said valve 59 is adapted to be unseated. In the drawings said handle is shown in a position, in which it has released the stem of valve 59.

As long as valve 59 is lifted, no pressure can be set up in pipe 5, so that the starting valve cannot be actuated and the fuel pump can draw 40 from the fuel tank in the ordinary manner. However, if handle 61 assumes its starting position shown in Fig. 5, valve 59 acts as a non-return valve so as to allow the pump to draw fuel from the fuel tank, but to check the reverse flow of the fuel and compel the fuel supplied by the pump to actuate the starting valve of the engine.

In order that the full quantity of fuel be delivered to the actuating plunger of the starting valve, it is necessary for the plunger 62 to be turned angularly into a position wherein, during normal operation of the engine, no fuel would be injected, i. e. into the position of zero stroke volume. Since it requires a higher pressure to open the fuel valve, than it does to actuate the starting valve, the latter only will be actuated.

The plunger 62 of the fuel pump is provided with a circumferential, helically wound groove or recess 63 (see also Fig. 5A), which by means of an axial groove 64 is in permanent communication with the pump chamber. In a predetermined position of the plunger, groove 64 registers with port 65, into which suction pipe 58 opens. The stroke volume of the pump can be controlled by allowing groove 63 to uncover port 65 at the desired moment during the cycle. As soon as this registration takes place, the amount of fuel delivered by the pump is by-passed through suction pipe 58, and further to the fuel tank through valve 59 which, during normal operation of the engine, is unseated by lever 61.

With a view to said control, plunger 62 is provided with a square portion 66, on which a gear 75

wheel 67 is slidably but non-rotatably mounted. Said gear wheel is adapted to be turned in either direction by a rack 68 mounted for lengthwise sliding motion.

5 The plunger 62 is driven in the ordinary manner by means of a cam 69 cooperating with a pusher 70, a coiled spring 70a serving for the return movement of the plunger.

When the engine is to be started, the rack 68 is placed in the position wherein the stroke volume is zero, and handle 61 is switched over into position 61'. With the rack 68 in said position, axial groove 64 permanently registers with port 65, so that suction pipe 58 is in permanent communication with the pump chamber and the total amount of fuel drawn from the fuel tank is forced during the working stroke of the pump, through pipes 58 and 5 to the starting valve of the engine, which is thereby opened in the manner described hereinbefore with reference to Fig. 1. During the return stroke of the pump plunger, the hydraulic plunger 24 of the starting valve 23 (Fig. 1) follows this movement, until the starting valve is seated and plunger 24 again sufficiently clears the valve rod 29.

The abutment of plunger 24 may be formed as a valve disc 24a for preventing any leakage by liquid from the hydraulic cylinder 25 during normal operation of the engine. Any fuel that still 30 should leak past valve 24a will be replaced, through valve 59, during the suction stroke of the pump.

During normal operation of the engine, the rack 68 is set in a position wherein plunger 62 covers port 65 during part of the working stroke. As long as port 65 is covered during said stroke, the fuel is forced, through pipe 4, to the fuel valve of the engine. If, however, during said stroke groove 63 uncovers said port, the pressure immediately falls to zero, since valve 59 is unseated by lever 61.

Fig. 6 illustrates still another arrangement in accordance with the invention. As shown, the suction pipe 14 from the fuel tank is connected 45 with the suction pipe 73 of the fuel pump through a piston valve formed by the plunger 71 for actuating the starting valve 23 of the engine. Plunger 71 is provided with a radial passage 74 which, during normal operation of the engine, connects 50 pipes 14 and 73. Said piston is further provided with a square portion 72, on which the hub portion 75a of a handle 75 is slidably but non-rotatably mounted. Consequently, said plunger is 55 adapted to be rotated about its own axis so as to cut off the connection between pipes 73 and 14.

If the fuel pump is set in a position wherein its stroke volume is zero, as described with reference to Fig. 5, so that the total amount of fuel drawn from the fuel tank is forced through pipe 60 73, then, with plunger 71 in the position shown, the fuel is by-passed through a passage 76 and permitted to act upon the top face of said plunger, whereby the starting valve is opened. A non-return valve 77 in the by-pass 76 prevents said 65 fuel from returning to the fuel tank.

I shall now proceed to describe an arrangement in which the change-over member is formed by the pump plunger itself, reference being had to Fig. 7 of the drawings. The wall of the cylinder 70 79 of pump 78 is provided with a suction port 80 and, diametrically opposed thereto, with a port 81. Connected to port 80 is the suction pipe 14, running to the fuel tank. Port 81 is connected with pipe 5 to the starting valve of the engine. 75 The delivery pipe 4 connects the fuel valve of

the engine with the pump chamber, through the medium of the delivery valve 82.

The pump plunger 62 is provided with an axial groove 64, which communicates with a circumferential helical groove 63 (see also Fig. 7C) and 5 opens into the pump chamber. The stroke volume of the pump is thus again determined by the angular position of the plunger and controlled, in the manner described with reference to Fig. 5, by means of a small gear wheel 67 slidably but 10 non-rotatably mounted on a square portion 68 of the plunger and meshing with a rack 68 adapted for manual sliding operation. The working stroke is brought about by a cam 83, the return stroke by a coiled spring 83a, as usual. 15

If the engine is to be started, rack 68 is moved through the required distance, whereby the plunger is turned until the axial groove 64 is in alignment with port 81 and port 80 remains covered during the cycle. The total amount of fuel 20 is now forced to the actuating plunger of the starting valve of the engine.

For starting the engine, the change-over handle operatively connected to rack 68 is moved to starting position. Thereupon, the starting valve 25 or one of the starting valves of the engine is lifted in the manner described hereinbefore.

When the engine is of the multi-cylinder type, or of the reversible type, I prefer to start it by means of a slideable cam or cam shaft. A reversible engine is ordinarily provided with a cam for the normal running direction, another cam for the reverse movement, and an intermediate or neutral cam, said cams being mounted on a common shaft slideable in axial direction. If 35 now said cams are united by portions having gradually sloping surfaces, the matter may be utilized, during sliding movement of the cams in the one or the other direction, starting from neutral position, to actuate the plunger of the pump, 40 and consequently the plunger of the starting valve.

Provided, therefore, that the starting air valve has been opened, the motor begins to run in the desired direction by air supplied through pipe 23a (Fig. 1), and the starting valves are further 45 automatically moved, by the fuel pumps, in the correct sequence and in the manner explained before. In connection therewith, reference is had to Figs. 7A and 7B, wherein the cams for forward running direction and for the reverse movement 50 are designated by 84 and 85, respectively. The cams may be shifted by means of the lever 85a.

In the arrangement shown in Fig. 8, the cylinder of the fuel pump 87 is provided with a port 86 connected to pipe 5 running to the top of the 55 cylinder of the plunger for actuating the starting valve 2. The pipe 4 here directly connects the pump chamber with the fuel valve 1. The fuel tank is connected, through suction pipe 14 and a suction valve 88, with the pump chamber 60 and further, through a passage 89a in the cylinder wall, with a port 89 in the said wall, through which the fuel can return when the effective portion of the working stroke is finished.

The pump plunger 90 (see also Figs. 8A and 65 8B) has a central axial passage 90a opening into the top face and is provided with a control port 91 in communication with said passage. The stroke volume here is again controlled by means of the change-over handle 94 having a hub portion 94a adapted for sliding movement over a 70 square portion 95 of the plunger 90, so that the latter can be manually turned about its own axis.

When said handle assumes its normal position, port 91, which is somewhat in the form of a par- 75

allelogram, is adapted to register with port 89, whereas port 86 remains covered during the whole cycle.

The plunger 90 may further be provided, in addition to port 91, with an elongated port 92, which also communicates with passage 90a and which, in starting position, is adapted to register with port 86 to supply oil under pressure to the starting valve of the engine. In that case, port 89 only serves for the control of the stroke volume.

In order that the starting valve of the engine may be opened quickly, and any air that may be enclosed in the fuel may be removed, the plunger 96 for actuating said valve may be arranged to perform, during the working stroke of the fuel pump 87, a quick downward movement until the starting valve has attained its maximum lift, and thereupon to uncover a circumferential groove 97 in its cylinder, into which groove opens an overflow pipe 98 to the fuel tank. Through said pipe 98, any excess of fuel and any air entrapped therein is returned to the fuel tank, so that the volume of the cylinder of the "passive" plunger 96 may be smaller than that of the fuel pump cylinder. The starting valve remains in its fully opened position, until a third port 93 provided in the plunger of the fuel pump and communicating with passage 90a registers with port 89, whereby the pressure in the pipe 5 and in the cylinder of plunger 96 is relieved, and the starting valve is again seated by a quick movement under the influence of the spring by which it is loaded.

The cam 99 for actuating the fuel pump has a steep sloping portion 100 dimensioned as required for the fuel injection during normal operation. Following said portion 100 are a concentric portion 101 and a short, steep slope 102 for bringing port 93 into register with port 89 so as to allow the starting valve to seat itself at the required moment. As shown in Fig. 8 the cam 100 is symmetrical, so that the engine is adapted to be reversed. Starting, controlling and stopping of the engine may be effected by means of one and the same handle 94. Stopping may also be effected by lifting suction valve 88 by means of a special handle 103.

In the various embodiments described hereinbefore, starting is effected by means of a tool or a handle, whereby the plunger of the fuel pump is forced into its cylinder to perform its working stroke, after the change-over handle has been set to starting position; alternatively, the starting valve of one of the cylinders is manually lifted, after the piston of said cylinder has been moved into the required position. With multi-cylinder engines, or with engines that repeatedly require to be started, it is desirable to provide for an arrangement allowing the engine to be started fully automatically, and irrespective of the positions of its pistons. To this end, a manually operated pump, a pressure accumulator, or another suitable device may be provided which, when the engine is in rest, supplies the energy required for lifting at least one of the starting valves. Said device may be common to all starting valves, provided that the pressure supplied thereby is adapted to be suitably distributed in accordance with the position of the crank shaft, for which purpose the plungers of the fuel pumps themselves may be used. Fig. 9 illustrates, by way of example, an arrangement of this type.

In this arrangement, a starting pump 104

serves for supplying the hydraulic pressure required for unseating one of the starting valves of the engine cylinders. Said starting pump has a plunger 105, by means of which hydraulic pressure may be supplied through pipe 106 and branch pipes 107, 108, 109 to the plungers 110 of the various fuel pumps, one of which only is shown. Pipe 106 opens into a port 111 in the cylinder wall of the fuel pump, which also has ports 112 and 113 connected with pipe 5 to 10 the starting valve casing of the parent engine cylinder and with a passage 114 to the fuel tank, respectively.

The plunger 110 of the fuel pump (see also Fig. 9A) is provided with ports 115, 116, 117, 15 all communicating with a central passage 110a opening into the top face of the plunger. Said ports are adapted, individually or in combination, to cooperate with the ports 111, 112, 113 in the cylinder wall.

Port 115 is so arranged and dimensioned that port 111 is uncovered only when the plunger of the fuel pump has nearly attained its top position and the change-over handle 94 assumes its starting position. The pressure set up by the starting pump 104 then forces liquid through pipe 106, port 111, port 115, central bore 110a of the plunger 110, port 116, port 112 and pipe 5 to the starting valve casing of the corresponding engine cylinder. See also Fig. 9B.

When change-over handle 94 assumes its normal position, ports 111 and 112 remain covered throughout the cycle, but in that case port 117 cooperates with port 113 in the manner described hereinbefore to control the amount of fuel forced to the fuel valve at each working stroke of the fuel pump.

The starting pump 104 is provided with a suction valve 118 and with a delivery valve 119, its plunger 105 being loaded by a spring 120 tending to force it into its lowermost position. Said plunger 105 is rigidly coupled with a piston 121 adapted to reciprocate in a cylinder connected near its bottom to a pipe 122, through which starting air may be supplied from a vessel 122a to produce the required hydraulic pressure.

For starting the engine, all that is required is opening the starting air valve 122b and moving change-over handles 94 of the fuel pumps into starting position, whereby compressed air from a vessel 122a is admitted through pipe 122 into the cylinder of piston 121 of the starting pump 104.

Thus, fuel in the space above the plunger 105 is forced through delivery valve 119 and through pipe 106 to the starting valve casing of that engine cylinder, whose fuel pump plunger is approximately in top position, it being understood that said plunger then acts as a distributing valve for the fluid supplied by pump 104. Thereupon, the starting valves of the other cylinders are automatically operated in their sequence as described with reference to the other embodiments.

When the engine has attained sufficient speed, the change-over handles 94 are returned into position for normal operation. The starting air supply to pipe 122 is then cut off and the pressure below piston 121 relieved by means of the three-way valve 122b, so that spring 120 forces said piston downward and plunger 105 draws fuel from the fuel tank through suction valve 118 and pipes 123, 14, whereupon the starting device is again ready for a next operation.

If, with a reversible engine, the fuel pumps are provided with separate cams for both running

directions, starting in the one direction can be effected in the same manner as starting in the other direction. If, however, only one symmetrical cam is used, which does not require to be moved axially for reversing the engine, the distribution of the hydraulic pressure supplied by the common starting pump or the like (104 in Fig. 9) cannot be effected by the fuel pump plungers. For that purpose a separate valve member is required, which, dependent upon the position of the crank shaft and upon the desired direction of rotation, supplies hydraulic pressure to the starting valve of one of the engine cylinders. A preferred embodiment thereof will be described with reference to Fig. 10 of the drawings.

The fuel pump 124 is connected by the delivery pipe 4 to the fuel valve of the engine cylinder. The starting valve casing of said cylinder is connected to pipe 5, which communicates with the fuel pump 124 through a piston valve 125. Provided in said casing 125 is a valve piston 126. Pipe 5 is in permanent communication, through a circumferential groove 147 in the inner wall 25 of the valve casing 125, and a passage 127, with a port 128 in the wall of the fuel pump cylinder. Into the space on top of valve piston 126, fuel is adapted to be supplied, through pipe 129, by a starting pump 104.

30 Valve piston 126 is provided with an angular passage 130, which normally is covered by the cylinder wall, but which is adapted to be brought into register with the port of pipe 5 when the starting pump 104 or the like forces liquid 35 through pipe 129 into the space on top of said valve piston. A spring 131 normally holds valve piston 126 in its top position, wherein a valve disk 132 provided at the bottom side of said valve piston prevents leakage. Said valve disk also serves 40 as an abutment for the valve piston. See also Fig. 10A.

Associated with the valve piston 126 is a push rod 133 adapted to engage cam 134 for the forward movement as soon as the starting pump 45 (104) or the like supplies hydraulic pressure. In addition to cam 134, a second cam 135 for the reverse motion is provided. Both cams are secured to a sleeve 136 adapted for lengthwise sliding motion on a shaft 137, but prevented from 50 rotation with respect thereto. See also Fig. 10A.

55 Shaft 137 is adapted to be driven by a gear 138 meshing with a gear 139 on the cam shaft 140 of the engine, shaft 140 being fitted with a cam 141 serving for driving the fuel pump 124. Sleeve 136 is adapted to be moved in the one or in the other direction by means of a reversing handle 142, so that either the cam 134, or the cam 135 can be caused to cooperate with push rod 133.

In addition to port 128, the wall of the fuel 60 pump cylinder comprises a port 146 connected through pipe 14 with the fuel tank.

65 Plunger 143 of the fuel pump is provided with ports 144 and 145 adapted to register with ports 128 and 146, respectively, said plunger being adapted to be turned about its axis by means of a change-over handle 94.

70 Port 145 corresponds to port 91 in Fig. 8A, whereas port 144 corresponds to port 92 in Fig. 8A. Both ports 144, 145 are in communication with a central axial passage 90a. When the change-over handle 94 assumes its normal position port 145 is adapted to register with port 146, whereas port 128 remains covered during the whole cycle. It will be clear that port 145 controls the amount of fuel forced to the fuel valve 75

at each working stroke. When the plunger is turned into its starting position port 144 is adapted to register with port 128 to supply oil under pressure through the conduit 5 to the hydraulic cylinder 25 of the starting valve. 5

The modus operandi of this arrangement is as follows.

Assuming that the multi-cylinder engine is to be started to run in forward direction, the reversing handle 142 is moved into a position 10 wherein all cams 134 are vertically below their push rods 133. Thereafter, the starting air valve (not shown) is opened, so that air pressure is supplied to the starting valve casings of the engine cylinders. If now the change-over handles 15 94 are placed in starting position, port 144 in each fuel pump registers with port 128, but port 146 remains covered during the whole cycle. The valve 122b for supplying compressed air from the vessel 122a to the air cylinder of the 20 starting pump 104 is then opened, whereby in the manner stated above liquid fuel is forced through pipe 129 to the tops of the valve pistons 126, which thus move down until their push rods 133 engage their cams 134. Thereby, passage 25 130 is brought into register with pressure pipe 5, but only in that piston valve 126 whose cam 134 allows of said downward motion, the arrangement being so that the engine cylinder corresponding to that special cam assumes the correct 30 starting position. Consequently, the liquid supplied by the starting pump 104 flows to the starting valve of that particular engine cylinder, whereby the engine is started. The starting valves of all the engine cylinders are then automatically operated by the corresponding fuel pump plungers. 35

After the engine has attained sufficient speed, the change-over handles 94 of the fuel pumps are returned to their normal positions and the starting air valve is closed, whereby the air cylinder of the starting pump is opened to atmosphere and springs 131 again move valve pistons 126 into top position. Owing to the rotation of the fuel 45 pump plungers by handles 94, ports 128 are covered and ports 145 allowed to cooperate with ports 146 so as to control the stroke volume of the fuel pumps.

What I claim is:—

1. In an internal combustion engine, a combustion cylinder fitted with a fuel valve and a starting valve, a hydraulic cylinder, a passive hydraulic piston movable in said hydraulic cylinder to open said starting valve, a plunger pump adapted to supply liquid fuel to said fuel valve, and manually operable means for establishing communication between the chamber of said pump and the said hydraulic cylinder so as to make the said plunger the active piston in the hydraulic system for opening the said starting valve. 60

2. In an internal combustion engine, a combustion cylinder fitted with a fuel valve and a starting valve, a hydraulic cylinder, a passive hydraulic piston movable in said hydraulic cylinder to open said starting valve at a predetermined hydraulic pressure, a plunger pump adapted to supply liquid fuel and inject it through said fuel valve into the said combustion cylinder at a hydraulic pressure exceeding the first said pressure, and manually operable means adapted, 70 while maintaining communication between the chamber of said pump and the said fuel valve, to establish communication between the said chamber and the said hydraulic cylinder so as to make the plunger of said pump the active pis- 75

ton in the hydraulic system for opening the said starting valve.

3. In an internal combustion engine, a combustion cylinder fitted with a fuel valve and a starting valve, a hydraulic cylinder, a passive hydraulic piston movable in said hydraulic cylinder to open said starting valve, a plunger pump adapted to supply liquid fuel to said fuel valve, a connecting pipe between said pump and said hydraulic cylinder, a port in said pump plunger in permanent communication with the pump chamber and manually operable means for adjusting the pump plunger in its cylinder, said means being adapted to bring said port in communication with said connecting pipe so as to make said plunger the active piston in the hydraulic system for opening the said starting valve.

4. In an internal combustion engine, a combustion chamber, a combustion cylinder fitted with a fuel valve and a starting valve, a hydraulic cylinder, a passive hydraulic piston movable in said hydraulic cylinder to open said starting valve, a plunger pump having a suction pipe and a delivery pipe and adapted through said delivery pipe to supply liquid fuel to said fuel valve, a suction valve in said suction pipe, manually operable means for opening said suction valve, a pipe connecting said hydraulic cylinder with the said suction pipe intermediate said suction valve and said pump, a port in said pump plunger in permanent communication with the pump chamber and manually operable means for adjusting the pump plunger in its cylinder, so as to bring said port into communication with said suction pipe.

35 5. In an internal combustion engine, a combustion cylinder fitted with a fuel valve and a starting valve, a hydraulic cylinder, a passive hydraulic piston movable in said hydraulic cylinder to open said starting valve, a plunger pump having a suction pipe and a delivery pipe and adapted through said delivery pipe to supply liquid fuel to said fuel valve, a connecting pipe between said pump and said hydraulic cylinder, a port in said pump plunger, a second port in said pump plunger, both ports being in permanent communication with the pump chamber, and manually operable means for adjusting the pump plunger in its cylinder so as to bring the first said port into communication with said connecting pipe during at least the first part of the working stroke of said plunger and to bring the second said port into communication with the said suction pipe during the last part of said stroke.

6. In an internal combustion engine, a combustion cylinder fitted with a fuel valve and a starting valve, a hydraulic cylinder, a passive hydraulic piston movable in said hydraulic cylinder to open said starting valve, a plunger pump having a suction pipe and a delivery pipe and adapted through said delivery pipe to supply liquid fuel to said fuel valve, a connecting pipe between said pump and said hydraulic cylinder, a port in said pump plunger, a second port in said pump plunger, both said ports being in permanent communication with the pump chamber, manually operable means for adjusting the pump plunger in its cylinder to bring the first said port into communication with said connecting pipe during at least the first part of the working stroke of said plunger and to bring the second said port into communication with the said suction pipe during the last part of said stroke, a port in said hydraulic cylinder intermediate the ends thereof, and a conduit connecting last said port with the 75 said suction pipe.

7. In an internal combustion engine, a plurality of combustion cylinders each fitted with a fuel valve and a starting valve, a hydraulic cylinder individual to each of said starting valves, a passive hydraulic piston movable in said hydraulic cylinder to open the starting valve, a plunger pump individual to each combustion cylinder and having a delivery pipe through which to supply liquid fuel to the fuel valve, means for driving said pump, a connecting pipe between the said pump and the hydraulic cylinder, means for producing independent hydraulic fuel pressure, conduits for connecting said pressure producing means with each of said hydraulic cylinders, a distributing member provided in each of said 15 conduits and associated with said driving means, and manually operable means for establishing communication between the chamber of each of said pumps and the hydraulic cylinder so as to make the said pump plungers the active pistons 20 in the hydraulic system for opening the said starting valves.

8. In an internal combustion engine, a plurality of combustion cylinders each fitted with a fuel valve and a starting valve, a hydraulic cylinder individual to each of said starting valves, a passive hydraulic piston movable in said hydraulic cylinder to open the starting valve, a plunger pump individual to each combustion cylinder and having a delivery pipe through 25 which to supply liquid fuel to the fuel valve, means for driving said pump, a connecting pipe between said pump and the hydraulic cylinder, means for producing independent hydraulic fuel pressure, conduits between said pressure producing means and each of said connecting pipes, a distributing valve provided in each of said conduits and adapted under the action of said independent hydraulic pressure to establish 30 communication between said conduit and the connecting pipe, means for associating said distributing valve with the said driving means, and manually operable distributing means for establishing communication between the chamber of each of said pumps and the hydraulic cylinder 35 so as to make the said pump plungers the active pistons in the hydraulic system for opening the 40 said starting valves.

9. In an internal combustion engine, a plurality of combustion cylinders, each fitted with a fuel valve and a starting valve, a hydraulic cylinder individual to each of said starting valves, a passive hydraulic piston movable in said hydraulic cylinder to open the starting valve, a plunger pump individual to each combustion cylinder having a suction pipe and a delivery pipe and adapted through said delivery pipe to supply 50 liquid fuel to the fuel valve, means for driving said pump, a connecting pipe between said pump and the hydraulic cylinder, a port in said plunger in permanent communication with the chamber of said pump, manually operable means for adjusting the said plunger so as to bring said port into communication with said connecting pipe, means for producing independent hydraulic pressure, conduits between said pressure producing means and each of said connecting pipes, a distributing valve provided in each of said conduits and adapted under the action of said independent hydraulic pressure to establish 55 communication between said conduit and the connecting pipe, and means associated with said driving means and adapted to prevent last said communication from being established unless the 60

said driving means assume a predetermined position.

10. An internal combustion engine comprising a combustion cylinder, a fuel valve thereon, a starting valve on said cylinder controlling a supply of compressed air, a hydraulic cylinder upon said combustion cylinder, a piston movable in said hydraulic cylinder for operating said starting valve, a pump for supplying liquid fuel to said fuel valve and means utilizing said liquid fuel for actuating said piston in said hydraulic cylinder to operate said starting valve.

11. An internal combustion engine comprising a combustion cylinder, a fuel valve thereon, a starting valve on said cylinder controlling a supply of compressed air, a hydraulic cylinder upon said combustion cylinder, a piston movable in said hydraulic cylinder for operating said starting valve, a pump for supplying liquid fuel to said fuel valve, said pump having a pump chamber, a conduit extending between said chamber and said hydraulic cylinder and means controlling said conduit whereby said liquid fuel actuated by said pump may serve for operating said starting valve.

12. An internal combustion engine comprising a combustion cylinder, a fuel valve thereon, a starting valve on said cylinder controlling a supply of compressed air, a second cylinder mounted upon said combustion cylinder, a piston movable in said second cylinder for operating

said starting valve, a pump for supplying liquid fuel to said fuel valve, said pump having a pump chamber, a conduit extending between said fuel valve and said chamber, a second conduit extending between said chamber and said second cylinder and change-over means controlling the flow of fuel in said conduits whereby during starting the force of said pump may be directed through said second conduit to actuate said piston in said second cylinder to operate said starting valve. 10

13. An internal combustion engine comprising a combustion cylinder, a fuel valve thereon, a starting valve on said cylinder controlling a supply of compressed air, a second cylinder mounted upon said combustion cylinder, a piston movable 15 in said second cylinder for operating said starting valve, a pump for supplying liquid fuel to said fuel valve, said pump having a pump chamber, a conduit extending between said fuel valve and said chamber, a second conduit extending 20 between said chamber and said second cylinder and means controlling the flow of fuel in said conduits whereby during starting the force of said pump may be directed through said second conduit to actuate said piston in said second cylinder to operate said starting valve, and means 25 for shutting off the feed of fuel through said first conduit to said combustion cylinder during the operation of the starting valve.
